Primary Examiner — John R Yeh

(74) *Attorney, Agent, or Firm* — LANWAY IPR SERVICES; Chun-Ming Shih

(57) **CLAIM**

The ornamental design for a steam mop as shown and described.

DESCRIPTION

FIG. 1 is a perspective view of a steam mop showing the new design;

FIG. 2 is another perspective view thereof;

FIG. 3 is a front elevation view thereof;

FIG. 4 is a back elevation view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view taken from the square area 9 in FIG. 1; and,

FIG. 10 is an enlarged detail view taken from the square area 10 in FIG. 1.

The broken lines in the figures are for the purpose of illustrating portions of the steam mop that form no part of the claimed design. Other broken lines in FIGS. 1, 9, and 10 illustrate enlargement indications and form no part of the claimed design.

1 Claim, 10 Drawing Sheets
